UNITED STATES PATENT OFFICE.

ROY H. ANDERSON, OF ALLENTOWN, PENNSYLVANIA, ASSIGNOR OF ONE-HALF TO
H. GIBSON HASTINGS, OF ALLENTOWN, PENNSYLVANIA, AND A. HARLAN ELLIOTT,
OF PHILADELPHIA, PENNSYLVANIA.

SHOE PROTECTOR.

1,403,474.

Specification of Letters Patent. Patented Jan. 17, 1922.

Application filed July 25, 1919. Serial No. 313,308.

To all whom it may concern:

Be it known that I, ROY H. ANDERSON, a citizen of the United States, residing at Allentown, in the county of Lehigh, State of Pennsylvania, have invented certain new and useful Improvements in Shoe Protectors, of which the following is a specification.

My invention relates to toe protectors for shoe soles and it is my purpose to provide a protector of this type through the instrumentality of which the toe portion of the sole of a shoe may be restored to its normal shape after being worn away and which may be applied by a person with ordinary skill, thereby saving the expense and trouble of having the shoe formally repaired.

It is my further purpose to provide a device of the character named, which, when applied to the sole of a shoe will be substantially invisible owing to the fact that it is so shaped and applied that certain surfaces thereof will form a continuation of the corresponding surfaces of the sole.

It is also my purpose to so construct the device that a portion thereof may be clinched into the upper surface of the sole to intensify the holding action of the protector and conceal all joints and in addition, keep the welt and sole together and protect the toe of the shoe against separating in wet weather.

With the above and other purposes in view the invention consists in the details of construction and in the arrangement and combination of parts to be hereinafter more fully described and particularly pointed out in the claims.

In describing the invention in detail reference will be had to the accompanying drawing wherein like characters of reference denote corresponding parts in the several views, and in which—

Fig. 1 is a perspective view of the toe protector of a shoe showing my invention applied;

Fig. 2, a longitudinal section of what is shown in Fig. 1;

Fig. 3, a perspective view of my improved toe protector detached;

Fig. 4, a longitudinal section of what is shown in Fig. 3; and

Fig. 5, a horizontal section through the

protector showing the tapering arrangement of the side portion thereof.

Referring to the drawing A indicates generally a shoe and B the sole thereof.

My improved protector is shown as comprising a metallic member including a base portion 10 which tapers substantially from its front to its rear and terminates in a knife edge 11. It will be observed however that the upper or inner surface 10' of the base portion is curved or dished and that this feature of my construction is of material advantage as it enables the protector to be applied without material trimming after wear of the toe portion of the sole as such worn portion always presents a curved or rounded face. This base portion 10 is provided with a screw opening or passage 12 and nail openings 13 and 14 whereby said base portion may be secured to the sole as clearly shown in Fig. 2. The toe protector also comprises a vertical side portion 15 which tapers from its front to the rear in the direction of either end. By tapering the base portion 10 as previously described the said base portion is materially thickened at its front, which part is of course subjected to the greatest wear. The toe protector further comprises an inwardly directed flange 16 at the upper end of the vertical side portion 15. This flange 16 is relatively thin and terminates in a knife edge 17.

In applying the protector to an unworn shoe the forward portion or rather the toe section of the sole B is chamfered correspondingly to the base portion of the protector so that when the latter is applied in place the bottom of said base portion will constitute a continuation of the bottom of the sole and render the structure substantially invisible. The same result is attained by cutting away the side edge of the sole to correspond with the taper of the vertical side portion 15. By making the flange 17 relatively thin it can be readily clinched into the upper surface of the sole as clearly shown in Fig. 2 and the sureness with which the protector is held in place greatly enhanced. In case where the sole is provided with prominent stitches on its upper surface or rather on the welt the flange 17 may be perforated as required to conform

with the stitches. Of course in applying the protector after wear no trimming of the base of the sole to correspond with the protector is necessary as has previously been 5 pointed out.

Where the welt is plain the flange 17 is correspondingly constructed as illustrated in the drawing. In other words the shape of the flange 17 may be varied according to 10 the particular construction of the upper surface of the sole with which it is associated, such variation being simply resorted to to secure a more exact fitting.

It will of course be understood that my 15 invention is not limited to the specific construction illustrated and described and that various changes can be resorted to without departing from the scope of the invention as defined in the claims.

20 What I claim is:—

1. A protector adapted to be secured to the toe portion of a shoe sole suitably reduced to receive it, comprising a metallic member including a base portion adapted to 25 underlie the sole, a vertical side portion adapted to embrace the edge of the sole, and an inwardly directed flange at the upper edge of the side portion adapted to overlie the adjacent top face of the sole, said bottom portion being thicker at its front than at its rear and said flange and the outer face of the bottom portion being disposed in parallelism throughout their extent whereby, in the secured position of the protector upon a sole suitably reduced to receive it, the vertical side portion forms an even continuation of the upper and lower 30 marginal edges of the sole, the bottom face of the member forms an even continuation of the bottom face of the sole and maximum wearing material is disposed at the point of greatest wear.
2. A protector adapted to be secured to the toe portion of a shoe sole suitably reduced to receive it, comprising a metallic member including a base portion 35 adapted to underlie the sole, a vertical side portion adapted to embrace the edge of the sole, said vertical side portion being thicker intermediately than at its ends and tapering from the front of the member rearwardly to a thin edge, an inwardly directed flange at the upper edge of the side portion adapted to overlie the adjacent top face of the sole, said bottom portion being thicker at its front than at its rear and said flange and the outer face of the bottom portion being disposed in parallelism throughout their extent whereby, in the secured position of the protector upon a sole suitably reduced to receive it, the vertical side portion forms an even continuation of the upper and lower 40 marginal edges of the sole, the bottom face of the member forms an even continuation of the bottom face of the sole and maximum wearing material is disposed at the point of greatest wear.

2. A protector adapted to be secured to the toe portion of a shoe sole suitably reduced to receive it, comprising a metallic member including a base portion adapted to underlie the sole, a vertical side portion adapted to embrace the edge of the sole, said vertical side portion being thicker intermediately than at its ends and tapering from the front of the member rearwardly to a thin edge, an inwardly directed flange at the upper edge of the side portion adapted to overlie the adjacent top face of the sole, said bottom portion being thicker at its front than at its rear and said flange and the outer face of the bottom portion being disposed in parallelism throughout their extent whereby, in the secured position of the protector upon a sole suitably reduced to receive it, the vertical side portion forms an even continuation of the upper and lower marginal edges of the sole, the bottom face of the member forms an even continuation of the bottom face of the sole and maximum wearing material is disposed at the point of greatest wear.

3. A toe protector adapted to be secured to the toe portion of a shoe sole comprising a metallic member including a base portion adapted to underlie the sole, and a vertical side portion adapted to embrace the edge of the sole, said vertical side portion being thicker intermediately than at its ends and tapering from the front of the member rearwardly to thin edges for the purpose set forth.

In testimony whereof, I affix my signature in the presence of two witnesses.

ROY H. ANDERSON.
